UNITED STATES PATENT OFFICE

ANTHONY H. GEUTING, OF MERION, PENNSYLVANIA

DESIGN FOR A SWEATER OR ANALOGOUS ARTICLE

Application filed December 17, 1931. Serial No. 42,115. Term of patent 14 years.

To all whom it may concern:

Be it known that I, ANTHONY H. GEUTING, a citizen of the United States, and a resident of Merion, in the county of Montgomery and State of Pennsylvania, have invented a new, original, and ornamental Design for a Sweater or Analogous Article, of which the following is a specification, reference being had to the accompanying drawing, forming part thereof.

I claim:

The ornamental design for a sweater or analogous article as shown and described. In testimony whereof, I affix my signature.

ANTHONY H. GEUTING.
